UNITED STATES PATENT OFFICE

EDWARD H. SCHANE, OF CLEVELAND, OHIO, ASSIGNOR TO THE FANNER MANUFACTURING COMPANY, OF CLEVELAND, OHIO, A CORPORATION OF OHIO

APPARATUS FOR FORMING METALLIC RETAINING MEMBERS

Application filed September 29, 1924. Serial No. 740,566.

This invention relates to apparatus for forming metallic retaining members, particularly chaplets such as employed for supporting the core of a mold.

5 More specifically the present invention relates to apparatus for applying heads to the stems of chaplets or other members of similar form in such manner that the head is rigidly held in place upon the stem.

10 It is quite important that chaplets which are used for supporting the core within an assembled mold prior to the pouring operation be so constructed that they will not be weakened by the heat of the molten metal until sufficient metal has entered the mold 15 to fill the cavity beneath the core and to support the core. Since the chaplets are melted and become part of the metal of the casting, it is also very important that they be 20 inexpensive.

It is the object of the present invention to provide apparatus by means of which chaplets of superior quality may be manufactured at a low cost.

25 More specifically it is the object of the invention to provide apparatus by which the attached head is securely fixed to the stem and supported by an annular shoulder formed upon the stem which is of such thickness that 30 it will not be weakened sufficiently by the heat of the molten metal to permit movement of the head on the stem and settling of the core before there is sufficient metal in the mold to support the core and also to provide

35 apparatus by which such chaplets can be manufactured at a rapid rate and at a very low cost.

With the above and other objects in view the invention may be said to comprise the apparatus as illustrated in the accompanying drawings hereinafter described and particularly set forth in the appended claims, together with such variations and modifications thereof as will be apparent to one skilled in 45 the art to which the invention appertains.

Reference should be had to the accompanying drawings forming a part of this specification in which Fig. 1 is a section taken on line 1—1 of Fig. 3 and showing a top plan 60 view of the bed of the press and the mecha-

nism mounted thereon; Fig. 2 is a central vertical section taken on line 2—2 of Fig. 1; Fig. 3 is a transverse vertical section taken on line 3—3 of Fig. 1; Fig. 4 is a section on line 4—4 of Fig. 1 showing the main portion of the machine in front elevation; Fig. 5 shows the blank from which the body portion of the chaplet is formed; Fig. 6 shows the blank after the shoulder upsetting operation; Fig. 7 shows the head applied to the shouldered blank and Fig. 8 shows the completed chaplet.

Referring first to Figs. 5 to 8 of the drawing, the chaplet which the present invention is designed to produce has a stem *a* and a head *b* integral with the stem and an attached head *c* which is secured to the upper end of the stem, as shown in Fig. 8, the stem having a relatively thick annular shoulder *d* against which the underface of the attached head *c* bears and the upper end of the stem being upset to secure the head *c* to the stem. In forming the chaplets, blanks such as shown in Fig. 5 are continuously fed to the machine in which the stem is first operated upon by upsetting dies which form an annular shoulder *d* upon the stem as shown in Fig. 6. The head *c* is then applied by a second set of dies which cause the stem to pierce the material of the head as indicated in Fig. 7 and finally by means of a third set of dies the projecting end of the stem is upset to firmly secure the head to the stem, thus forming the complete chaplet as shown in Fig. 8.

The above described operations are performed successively upon the individual chaplet blanks as they are fed through the machine, the blanks being so fed and the machine so operated that the three operations are performed simultaneously upon three successive blanks.

The forming operations are performed by means of a press which has a bed 1 and a head 2 which reciprocates toward and from the bed. The blank feeding mechanism is mounted upon the bed of the press and is operated by means of an upright shaft 3 which is journaled in the bed centrally thereof. Fixed to the upper end of the shaft 3 is a disk 4 which bears upon the bottom of a circular 100

recess 5 formed in the upper face of the bed. The disk 4 has a series of regularly spaced die forming plates 6 secured at regular intervals to the upper face thereof, the outer ends of the die plates 6 extending to adjacent the periphery of the disk and having undercut notches 7 at their outer ends adapted to receive the heads *b* of the chaplet blanks and semi-circular notches 8 in the outer edges thereof adapted to receive the stems *a* of the blanks. The notches or recesses 8 in the outer ends of the die plates 6 serve as pockets for positioning the chaplet blanks at regularly spaced points about the periphery of the disk and cooperating with the die plate 6 are three 10 slidable die plates 9, 10 and 11 which are mounted upon the bed outside the periphery of the disk for movement radially with respect to the disk toward and from the periphery thereof. The movable die plates 9, 10 and 11 have the same angular spacing with respect to the disk as the die plates 6 upon the disk and each of these plates has upon its inner edge a semi-circular recess 8^a which 20 engages the stem of a blank held by the die plate 6 of the disk to clamp the blank during the forming operations, the die plates 6 and 9 forming the dies upon the bed which cooperate with suitable dies carried by the head. Means are provided for intermittently imparting a rotative movement to the disk 4 at predetermined intervals, each movement being just sufficient to advance a die plate 6 from a position in alignment with one of the 30 slidable die plates on the bed to a position in alignment with the next slidable die plate. As shown herein the disk 4 has four die plates 6 and is adapted to hold four blanks spaced 90° apart thereon and the movement 40 imparted to the disk upon each actuation will therefore be through an angle of 90°. The rotary movements are imparted to the disk 4 through a helical gear 12 fixed to the lower end of the shaft 3 which meshes with a helical gear 13 on a transverse shaft 14 beneath the bed, the shaft 14 being actuated by a pawl and ratchet operated by the head actuating mechanism of the press. The pawl and ratchet mechanism comprises an arm 15 pivoted on the shaft 14 and carrying a pawl 15^a 50 which engages with the ratchet 14^a on the shaft 14 and is pressed toward the ratchet by a spring 15^b. The pawl rides over the ratchet during downward movement of the arm 15 but engages the same during the upward movement thereof so that rotation is imparted to the shaft 14 during the upward movement of the arm, the arm 15 being connected to the head actuating mechanism by a connecting rod 16 so that the actuation of the disk occurs during upward movement of the head.

The cross-head or ram 2 of the press has attached to the lower end thereof a plate 17 to the underside of which are attached dies

18, 19 and 20 which are so positioned that upon downward movement of the head they will engage with the stems *a* of the blanks which are held between the die plates 6 of the disk and the plates 9, 10 and 11 of the bed. In addition the plate 17 carries depending wedge bars 21, 22 and 23 which when the head is lowered to bring the dies into engagement with the work project into openings 24 formed in the bed. Each of the depending wedge members has an inclined cam face 25 upon the inner side thereof, these cam faces serving to shift the slides 9, 10 and 11 toward the disk 4, the slides 9 and 11 being provided with rollers 26 at their outer ends which engage with the inner faces of the wedge members 21 and 23 and the slide 10 being provided with rollers 27 which engage with the wedge members 22, the slide 10 being actuated by a pair of spaced wedge members 22 to permit feeding a strip of material for forming the attached head of the chaplets as will be hereinafter more fully explained.

The outer faces of the wedge members 21 and 23 engage with bearing plates 28 which are adjustably mounted in the bed and the outer faces of the wedge members 22 engage with a similar bearing plate 29 which is also adjustably mounted. The slides 9, 10 and 11 are normally held in their outermost positions by coil springs 30 which are interposed between the inner ends of the slides and stripper plates 31 which are held in engagement with the periphery of the disk 4 by the springs. The stripper plates 31 are mounted below the die plates 9 and, when the die plates are in clamping position in engagement with the stems of the chaplets, the plates 31 are beneath the inner ends of the die plates so that when the slides are released, the stripper plates 31 which project slightly above the portion of the disk upon which the chaplets rest, will prevent movement of the chaplets with the die plates. The springs 30 are mounted at their inner ends upon a stem 32 projecting outwardly from the stripper plates 31 and at their outer ends in the recess 33 formed in the slides upon which the die plates are carried. During the downward movement of the head the rollers 26 and 27 of the slides are engaged by the inclined cam faces 25 of the actuating members 21, 22 and 23 and are moved inwardly to bring the die plates 9, 10 and 11 into engagement with the die plates 6 of the disk which have, during the upward movement of the head, been moved into alignment with the respective radially movable die plates, to firmly hold the stems of the chaplets in position to be engaged by the descending dies 18, 19 and 20. As the head begins its upward movement, the cam faces 25 are moved out of engagement with the rollers and the slides are shifted out of engagement with the disk and the chaplets thereon by the springs 30 so as not to interfere with the

rotary movement of the disk which is imparted thereto during the upward stroke of the head.

It is apparent that chaplet blanks supplied to the disks 4 will be acted upon successively by the dies 18, 19 and 20. The die 18 is an upsetting die which has a central recess to receive the upper end of the stem and an annular recess surrounding the central recess to receive the metal forced outwardly by the downward pressure of the die upon the stem and form the annular shoulder *d* intermediate the upper and lower ends of the stem. The die 19 is the head applying die which acts to press the end of the sheet metal strip upon the upper end of the stem of the blank causing the stem to pierce the strip and also has a cutter cooperating with a cutter block fixed to the bed for severing the pierced end portion of the strip to form the head of the chaplet. The die 19 has a central aperture 34 to receive the upper end of the chaplet stem after the stem has been forced through the sheet metal strip and has a squared rear edge 35 which cooperates with a stationary cutter block 36 on the bed to sever the strip. The sheet metal strip from which the chaplet heads are formed is intermittently fed between the actuating arms 22 into the space between the die 19 and the die members on the bed with which the die 19 cooperates by means of feed rollers 37 which are suitably supported on the frame of the machine at the rear of the press. Means are provided for imparting a turning movement to the rolls 37 during each upward movement of the head to feed the strip a predetermined amount. The rolls 37 are actuated by means of a ratchet 38 fixed to one of the rolls which is engaged by a pawl 39 carried by a pivoted arm 40 which is connected at its upper end by a link 41 to a bell crank lever 42 which is pivoted to the frame and has a pin and slot connection 43 to the plate 17 of the head. Upon each actuation of the head the sheet metal strip is fed forward a predetermined amount so that the end thereof overlies the upper end of the stem of the chaplet blank and during the downward stroke of the head, the portion of the strip projecting in front of the cutter block 36 is severed by the rear edge of the die 19 and the severed piece is forced downwardly upon the upper end of the stem, the stem acting as a punch and piercing the piece, and the severed piece of the strip which forms the head *c* of the chaplet being forced downwardly into snug engagement with the shoulder *d* which has previously been formed on the stem by the die 18. The slugs cut from the pieces forming the heads of the chaplets are pushed upwardly in the opening 34 of the die 19 and the plates 17 and head 2 are provided with a passage 44 through which these slugs are pushed during the operation of the machine.

The die 18 forms the original blank such as shown in Fig. 5 into the shape shown in Fig. 6 and the die 19 applies the head *c* to the shouldered stem as shown in Fig. 7. The blanks are fed from the position in which they are acted upon by the die 19 into a position in which they are acted upon by the die 20 which is an upsetting die which flattens out the portion of the stem projecting above the head *c* to securely fasten the head in place upon the stem, the head *c* being held firmly against the annular shoulder *d* upon the inner side thereof. After being operated upon by the third die 20, the chaplets are completed and during the next actuation of the disk are discharged from the machine by means of an ejector arm 45 which overlies the disk and deflects the chaplets from the disk into a discharge opening 46 formed in the bed 1.

Means are provided for continuously feeding chaplets one at a time to the peripheral pockets of the disk 4, the feed device comprising a feed disk 47 which is rotatably mounted adjacent the disk 4 and provided with a pair of diametrically disposed peripheral pockets 48 which register during the operation of the machine with the successive retaining notches 8 of the disk 4 and deliver the chaplet blanks thereto. The feed disk 47 is driven in a direction opposite that of the disk 4 by means of gears 49 and 50 which are attached to the disks 4 and 47 and are in mesh with each other. The adjacent peripheral portions of the two disks are thus caused to move in the same direction and the relative rate of rotation of the two disks is such that the pockets 48 register with the successive notches 8 on the disks 4, the disk 47 being turned through one half a revolution, while the disk 4 is turned through a quarter of a revolution. The transfer of the chaplet blanks from the disk 47 to the disk 4 is effected by a transfer plate 51 fixed to the bed and overlying the disk 47, the inner edge of the plate 51 being shaped to conform to the periphery of the disk 4 so that the blanks are held in engagement with the die plates 6 after they have been moved into engagement therewith by the disk 47 and thus transferred from the disk 47 to the disk 4. The chaplet blanks are supplied to the feed disks 47 by means of a chute 52 which has an undercut slot 53 to receive the heads of the blanks, the chute 52 being kept full of blanks by suitable mechanism in a hopper at the upper end thereof as well understood in the art. The chute is so disposed with respect to the feed disk 47 that the disk moves across the lower end of the chute and the pockets 48 are so formed that as each pocket moves across the lower end of the chute it will extract one blank therefrom, the chute being so formed as to deliver the blanks in upright position with the stems thereof in position to engage in the pockets of the disk.

It is desirable that means be provided for preventing the operation of the press in the event that the supply of blanks is interrupted or in the event that a defective or improperly positioned blank is delivered to the feed disk, since otherwise the material which forms the attached heads of the chaplet would be wasted and the operation of the dies upon improperly positioned blanks or loose pieces of metal might damage the machine. Means are therefore provided for automatically stopping the machine either upon interruption of the supply of blanks or upon delivery of any improperly positioned or defective blank to the feed disk. This safety device comprises an arcuate plate 54 which overlies the peripheral portion of the disk 47 about which the blanks are moved during the transfer thereof from the chute to the main disk 4, the plate 54 being carried by an arm 55 which is pivoted at 56 intermediate its ends to the bed and has an outer end portion which is engaged by a coiled spring 57 which tends to shift the outer end of the arm upwardly and to move the arcuate plate 54 downwardly toward the disk 47. The stem of each chaplet blank during its passage from the chute 52 to the disk 4 engages the underside of the plate 54 and forces the plate upwardly in opposition to the spring 57. The outer end of the arm 55 underlies an adjustable contact member 58 and when the blanks are properly feeding is held out of contact with the contact member by the blanks. If, however, one of the pockets 48 of the disk should fail to receive a blank or the blank should become improperly positioned, the outer end of the arm 55 will be rocked upwardly by the spring 57 and caused to engage with the contact member 58. The arm 55 and contact members 58 are connected in the circuit of a solenoid 59 so that the solenoid is energized whenever the arm 55 is moved into engagement with the contact 58. The core of the solenoid 59 is connected to the horizontally extending arm 60 of the bell crank lever which is pivoted to the bed 1 and has an upwardly extending arm 61. The operation of the press is controlled by a suitable clutch which is operated by the lever 62, the lever or clutch being provided with a spring acting in a direction to normally hold the clutch in disengaged position. The clutch is moved into engagement with a bracket 63 mounted upon the bed 1. By shifting the lever 62 downwardly and engaging the same with the bracket 63, the machine may be started into operation and will continue to operate as long as the blanks are properly fed by the feed disk 47. Whenever there is an interruption in the feed of the disks or a disk fed to

the pocket 48 becomes improperly positioned the arcuate plate 54 will be permitted to move downwardly toward the disk causing the circuit of the solenoid 59 to be closed whereupon the core of the solenoid will be actuated causing the arm 60 of the bell crank lever to swing upwardly and the upright arm 61 thereof to swing outwardly into engagement with the lever 62 pushing the same outwardly out of engagement with the retaining portion of the bracket 63 causing the entire mechanism to be stopped so that the operator may do whatever may be necessary to reestablish the proper feeding of the blanks.

Having described my invention, I claim:

1. A machine for applying a head to the stem of a metallic retaining member comprising means for forming a shoulder on the stem intermediate the ends thereof, means for applying a head to the stem, means for upsetting the end of the stem to secure the head in place thereon against the shoulder, and means for feeding the stem to the shoulder forming means, from the shoulder forming means to the head applying means and from the head applying means to the upsetting means.

2. A machine for applying heads to the stems of metallic retaining members, comprising means for forming shoulders on the stems intermediate the ends thereof, means for forcing the ends of the stems through a sheet metal body and for severing the pierced portions of the body to form the heads, means for upsetting the ends of the stems to secure the heads in place, and means for feeding each stem successively to the shoulder forming means, from the shoulder forming means to the head applying means and from the head applying means to the upsetting means.

3. A machine for applying heads to the stems of metallic retaining members comprising a pair of upsetting dies adapted to form an annular shoulder upon the stems, a pair of head forming and applying dies spaced from said first mentioned dies, means for feeding the material from which the heads are formed between said last mentioned dies, a pair of upsetting dies spaced from the second pair of dies for upsetting the ends of the stems to secure the heads in place, and means for successively and separately advancing each member from the first pair of dies to the second and from the second pair of dies to the third.

4. A machine for applying heads to the stems of metallic retaining members comprising a bed, a carrier associated with the bed, means for intermittently actuating the carrier, die forming means on the bed cooperating with the carrier in the positions at which the carrier is at rest to form a plurality of dies, movable dies cooperating with the dies on the bed, means associated with one pair of cooperating dies for applying heads to the stems and means associated with another

pair of dies for securing the heads to the stems.

5. In a machine of the character described, a bed, a carrier on the bed having at its edge 5 a series of equally spaced article holding pockets, spaced members on the bed cooperating with said pockets to form dies, means for intermittently moving said carrier to successively position the articles in predetermined positions, a head movable toward 10 and from the bed, means for actuating the head during the intervals between the actuations of the carrier, and dies carried by the head positioned to simultaneously engage a plurality of articles.

6. In a machine for applying heads to the stems of metal retaining members, the combination with a press having a bed and a head movable toward and from the bed, spaced 20 dies carried by the head, means associated with the bed for forming dies aligned with the dies of the head and for successively positioning the stems in the dies of the bed, means for actuating the head, and means associated with one set of dies for applying heads to the stems, the other of said sets of dies being adapted to upset the stems for securing the heads in place thereon.

7. In a machine for forming metallic retaining members, the combination with a press having a bed and a head movable toward and from the bed, of a carrier disk rotatably mounted on the bed, said disk having regularly spaced peripheral notches 30 adapted to receive said members, means for feeding a retaining member to each of the notches of the disk during rotation thereof, movable die forming means at spaced intervals on the bed adapted to engage with said members, dies carried by the head adapted to cooperate with the dies on the bed, means for alternately actuating the head and carrier, and means operated by the head in its movement toward the bed for actuating the 40 movable die forming means.

8. In a machine of the character described, the combination with a press having a bed and a head movable toward and from the bed, 50 a disk rotatably mounted on the bed, said disk having regularly spaced peripheral notches, adapted to engage articles on the bed and move the same over the bed, guiding means on the bed adjacent the periphery of the disk, die forming members mounted on the bed and for movement radially toward and from the periphery of the disk, said die forming members being regularly spaced, dies carried by the head and positioned to cooperate with the dies on the bed, means for reciprocating the head and means for actuating the disk during upward movement of the head to successively align the notches with 60 the die forming members and means operated

by the head for shifting the movable die forming members.

9. In a machine of the character described, the combination with a press having a bed and a head movable toward and from the bed, 70 of a carrier disk rotatably mounted on the bed, said disk having a plurality of regularly spaced notches adapted to receive articles to be operated upon, a die forming means slidably mounted on the bed and movable toward and from the periphery of the disk, means for intermittently actuating the disk to bring the notches thereof successively into alignment with the die forming means, means for moving the head toward the bed in the intervals between the movements of the disk, means operated by the head for shifting the die forming means into engagement with the disk and a stripper associated with the die forming means to prevent movement of the 80 article with the die forming means upon movement thereof away from the disk.

10. In a machine of the character described, the combination with a press having a bed and a head movable toward and from the bed, of a disk rotatably mounted upon the bed, said disk having regularly spaced peripheral notches adapted to receive articles to be operated upon, means associated with the bed for retaining the articles in the notches, forming means carried by the head adapted to engage with the articles held in the notches of the disk, means for actuating the head and for imparting a rotative movement to the disk during the intervals between the operating strokes of the head, a feed disk on the bed having a plurality of regularly spaced peripheral notches, means for actuating the feed disk from the first mentioned disk to cause the notches of the feed disk to successively register with the notches of the first mentioned disk, and means for feeding articles to the notches of the feed disk.

11. In a machine of the character described, the combination with a press having a bed and a head movable toward and from the bed, of a rotary disk mounted on the bed and provided with regularly spaced peripheral notches, slides carried by the bed and movable toward and from the periphery of the disk, said slides having notches adapted to register with notches of the disk and to engage articles held therein, means actuated by the head for turning the disk to successively bring the notches thereof into alignment with said slides, dies carried by the head engageable with articles held between the slides and disk, and wedge members carried by the head and engageable with the slides to move the same 110 into engagement with the disk.

12. In a machine for applying heads to the stems of metallic fastening members, the combination with a press having a bed and a head movable toward and from the bed, a ro- 120

tatable disk arranged on the bed, a plurality of dies, said dies comprising die forming members arranged on said disk and cooperating movable die forming members arranged on said bed, means for intermittently rotating said disk for successively advancing the die forming members carried thereby into cooperating position with the die forming members on the bed, dies on the head cooperating with the dies on the bed, means operated by the head for intermittently feeding a strip of sheet metal over one of the dies on the bed, and means associated with a die on the head for cutting off a piece of said strip after each actuation thereof and for applying the severed piece to the stem.

In testimony whereof, I hereunto affix my signature.

EDWARD H. SCHANE.
